UNITED STATES PATENT OFFICE

LEOPOLD MAMBOURG, OF LANCASTER, OHIO, ASSIGNOR TO LIBBEY-OWENS GLASS COMPANY, OF TOLEDO, OHIO, A CORPORATION OF OHIO

NONREVERSIBLE FURNACE

Application filed October 10, 1925. Serial No. 61,669.

The present invention relates to glass apparatus, and has particular reference to a glass melting tank.

An important object of the invention is to provide a furnace having a plurality of ports arranged on each side of the furnace, each port being adapted to be in operation at all times.

Another object of the invention is to provide a furnace of this nature wherein each port is associated with a plurality of air supplying means in a manner that the air supply can be furnished alternately so that pre-heated air can be used similar to the manner in which preheated air is used in the regular regenerative type of furnace.

Still another object of the invention is to provide a furnace of this nature including a plurality of ports arranged along opposite sides of the furnace, said ports having a double checkerwork and air supply conduits associated therewith so that each port can be alternately furnished with air from a different conduit ever so often to permit the exhaust gases issuing from the furnace to alternately heat one checkerwork or the other, depending upon which checkerwork is in operative association with the port.

A further object of the invention is to provide a furnace adapted to more uniformly and economically condition a mass of molten glass from which a sheet may eventually be drawn, or from which any type of glass article can be produced.

Another very important object of the invention is to provide a glass furnace capable of maintaining the glass at a uniform temperature throughout the width of the furnace by reason of a continuous fire running clear across the tank at all times and throughout the length of the same.

Still another object of the invention is to provide a furnace having a plurality of ports which are arranged in a manner that absolute and accurate control at each port can be had of the amount of fuel introduced at that port in order to create a certain temperature at any one point throughout the length of the tank.

Other objects and advantages of the in-

vention will become apparent during the course of the following description.

In the drawings wherein like numerals are employed to designate like parts throughout the same,

Fig. 1 is a top plan view in section, illustrating the invention,

Fig. 2 is a section taken on line 2—2 in Fig. 1, looking in the direction of the arrows,

Fig. 3 is a fragmentary vertical sectional view through a portion of the furnace, and

Fig. 4 is a side elevation thereof.

This furnace is particularly adapted to overcome the great loss of heat from the fuel used in glass furnaces. Furnaces heretofore have been designed to facilitate use of the particular types of heating means used, and it is well known that radiation from the crown and side walls of these furnaces causes a waste in the heat which cannot be entirely satisfactorily overcome by the use of a heat insulation material.

In the old types of heating means the character of the flame and distribution of the flame over the glass in the tank would not permit of the greatest efficiency, either from the angle of fuel consumption or the quality of glass produced. The manufacture of glass in the form of sheets is almost a question of temperature control from the time the batch is introduced within the furnace until the glass has been drawn away in sheet form and annealed. Temperature changes in the glass appear to be detrimental to the production of good glass, and this furnace is designed to eliminate as far as possible undesirable rapid temperature changes in the molten glass being conditioned.

The high crown used in the usual furnaces is almost necessary if the large volumes of fuel are to be introduced as in the reversible or regenerative type of furnace. In this type of furnace the fuel is introduced from one side and then the other side. At no times are both sides of the furnace being worked at once. In view of the high crown and large volume of fuel the radiation from the crown on the glass is irregular as the fuel volume is too thick for radiated heat to penetrate in an efficient manner.

In the old type of regenerative furnace ports are arranged along both sides of the melting end of the tank. Means are provided for supplying gas and air, the gas usually being supplied through a pipe while the air is drawn through a checkerwork which has been previously heated by the exhaust gases issuing from the opposite side of the furnace. At intervals, usually about 20 minutes, the tank is reversed, that is the flame is stopped on one side and is started on the opposite side so that the glass is being heated from flame supplied alternately from one side and then the other. In view of the large amount of fuel introduced a like large amount of air must be used so that combustion does not actually take place until the gases are pretty nearly half across the tank. When the heat is applied from one side of the furnace, conditions are created which are rapidly changed when the opposite side is placed into operation. The lapse between the change over is in the neighborhood of about a minute. In this lapse of time considerable changes take place, which changes occur regularly at 20 minute intervals. In this way conditions which have been set up and working nicely are rapidly changed over and the glass and heat must again adapt themselves to another condition which is then rapidly changed to the first condition and so on.

In the present invention the tank is preferably designed to have a lower crown so that radiation from the crown will be more beneficial to the glass and will cause a decided saving in fuel consumption. Instead of the large ports spaced rather far apart, I propose to use a number of relatively smaller ports arranged closer together and extending preferably the entire length of the furnace. In this way a better distribution of the fuel with consequent uniform heating of the glass is obtained. The flames issue from both sides of the furnace simultaneously and continuously. Of course in this arrangement the ports nearer the intake end will ordinarily be fired to a higher temperature than the ports nearer the refining end.

In the drawings the numeral 5 designates a tank furnace which may be provided with the exit end 6. The tank 5 is shown in Fig. 2 as containing a mass of molten glass 7. The batch which comprises the ingredients from which the glass is produced may be introduced in this furnace through the openings 8 formed in the side walls of the tank. The batch is subjected to the action of the flames which causes the batch to melt to produce molten glass. As the glass is continuously or substantially continuously drawn off from the discharge end 6 the glass gradually moves toward this end. This permits the molten glass to become refined and in condition for working.

65 A plurality of ports 9 are arranged along

both sides of the tank 5 and preferably extend along the entire side. The number of ports illustrated is not to be taken as a limitation to the number of ports which can be efficiently used. Each port is provided with a gas supplying channel 10, the gas entering as indicated by the arrows. Air conduits 11 run past each of the ports as clearly shown in Fig. 1. Each air conduit 11 branches off into a two-way passage forming the passages 12 and 13. A valve 14 is located at the end of the single passage 11 to permit the passage 11 to be in operative communication with either passage 12 or passage 13. Each of the passages 12 and 13 has associated therewith a checkerwork 15.

The stack 16, shown in Fig. 4, is in communication with the compartment 17 shown in Fig. 1, while a flue 18 is associated with the compartment 19. A valve 20 is arranged between the compartments 17 and 19 to permit the passageways 21, 22, 23 and 24 to be thrown into operative communication with either the stack 16 or flue 18. In Fig. 1 the arrows with the unbroken lines indicate the incoming air or gases showing the fresh air being drawn in through the stack down into the compartment 17, passing into the passages 21 and 22 respectively, through the two outer checkerworks where the air is pre-heated, then passing through the conduits 12 through passage 11, and into the ports 9 where the gas and heated air combine to produce a flame. The products of combustion are removed through the ports 25, communicating with the various conduits which convey the gases through the other checkerworks of each set of ports, after which they may be disposed of. The arrows with the broken lines indicate the path of the exhaust gases when the valves are arranged as shown in heavy lines. At intervals the valves 14 and 20 can be reversed so that the fresh air can be passed through the checkerwork previously heated by the exhaust gases. Although the air supply can be reversed, there will be no apparent interruption to the flames issuing from the ports. The gas supply remains constant while the air as far as the passage 11 remains constant. The ports 9 on both sides of the tank are preferable at all times in operation so that the glass is heated from both sides of the furnace and not from one side. Dampers 26 may be used to control the amount of air used, so that each port can be independently controlled to give the best results, the adjustment of the port depending upon its location. The numeral 27 indicates the pipe through which the gas coming in through the channels 10 is discharged.

With this type of furnace the various ports can be regulated to give the best results. Once a satisfactory adjustment, there is no need for readjustment until conditions

change. This is a decided advantage over the usual type of regenerative furnace.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

10 I claim:

1. A regenerative furnace of the character described, comprising a plurality of ports, means for supplying gas to the ports, and a plurality of reversible means for supplying air to each port.

2. A regenerative furnace of the character described, comprising a plurality of ports, means for supplying gas to the ports, a plurality of reversible means for supplying air to each port, and means for controlling said air supplies.

3. A furnace of the character described, comprising a plurality of ports, means for supplying gas to the ports, a plurality of means for supplying air to each port, and means for alternately supplying air to the ports from said supplying means.

4. A regenerative furnace of the character described, comprising a plurality of ports, means for supplying gas to the ports, a plurality of reversible means for supplying air to each port, and means for preheating the air before it mixes with the gas.

5. A regenerative furnace of the character described, comprising a plurality of ports, means for supplying gas to the ports, a plurality of reversible air supplying means associated with each port, and independent pre-heating means associated with each of the air supplying means for said ports.

6. A furnace of the character described, comprising a plurality of ports, means for supplying gas to the ports, and means for substantially continuously supplying air to each port from one of a plurality of supplies.

7. A furnace of the character described, comprising a plurality of ports, means for supplying gas to the ports, and means for substantially continuously supplying pre-heated air to each port from one of a plurality of supplies.

8. A furnace of the character described, comprising a plurality of ports, means for supplying gas to the ports, and means for substantially continuously and alternately supplying preheated air to each port from a plurality of air supplies.

9. A furnace of the character described, comprising a plurality of ports arranged along both sides of the furnace, means for supplying gas to each port, an air conduit associated with the ports, a plurality of passages connecting with said air conduit, and means for controlling which of the passages

is to be in operative communication with the conduit.

10. A furnace of the character described, comprising a plurality of ports arranged along both sides of the furnace, means for supplying gas to the ports, an air conduit associated with the ports, a pair of passages connecting with the air conduit, and a checkerwork construction associated with each passage.

11. A furnace of the character described, comprising a plurality of ports arranged along both sides of the furnace, means for continuously supplying gas to the ports, means for substantially continuously supplying air to all of the ports simultaneously, means for preheating the air, and means for alternating the source of air supply without affecting the supply to said ports.

12. A furnace of the character described comprising a plurality of ports, means for supplying gas to the ports, and means for alternately supplying pre-heated air to each port from a plurality of air supplies.

13. A furnace of the character described comprising a plurality of ports, means for supplying gas to the ports, and means for supplying pre-heated air to each port from alternate sources of supply.

14. A furnace of the character described, comprising a plurality of ports arranged along both sides of the furnace, means for supplying gas to the ports, an air conduit associated with the ports at each side of said furnace, a pair of air supplying passages connecting with the conduit, a checkerwork construction associated with each passage, reversible means for controlling which of the passages is to be in operative communication with the conduit for supplying air thereto, and means for receiving the exhaust gases from the furnace and causing them to pass through that passage not in operative communication with the conduit to effect a heating of the checkerwork associated therewith.

Signed at Lancaster, in the county of Fairfield, and State of Ohio, this 6th day of October, 1925.
